United States Patent Office

Des. 221,730

Patented Sept. 7, 1971

221,730

CLIP FOR SEALING PACKAGES AND THE LIKE

James W. Marietta, Jr., D-Mar, 116 W. 24th St.,
Los Angeles, Calif. 90007

Filed Sept. 18, 1969, Ser. No. 19,200

Term of patent 14 years

Int. Cl. D8—03, 04

U.S. Cl. D8—266

FIG. 1 is an isometric view of a clip for sealing packages and the like showing the front, one side and bottom end thereof.

FIG. 2 is a front elevation thereof.

FIG. 3 is a top view thereof.

FIGS. 4 and 5 are views of the opposite sides thereof, and

FIG. 6 is a bottom view thereof.

I claim:

The ornamental design for a clip for sealing packages and the like, as shown.
